HINGED PRESSURE ROLLER AND PAPER
GUIDE FOR DUPLICATOR CARRIAGES

Alfred Marchev, La Grange, Ill., assignor to
Ditto, Incorporated, Chicago, Ill., a corporation
of West Virginia

Application May 11, 1934, Serial No. 725,035

12 Claims. (Cl. 101—133)

This invention relates to duplicating machines and more especially to those of the hectograph type.

The invention may be embodied for example in 5 a machine similar to the one disclosed in the copending application of Marchev and Hernlund, Serial No. 663,404, filed March 29, 1933.

In machines of this type, there is provided a platen with a gelatin or hectograph band supported thereon and a movable carriage above the same 10 provided with a platen roller and a pressure roller cooperating to feed sheets of paper onto the surface of the gelatin band. The platen roller is supported on a yoke which is rocked to move the 15 roller upwardly and downwardly. When the roller is moved downwardly, it engages the paper and cooperating with the pressure roller forces one edge of the paper into contact with the duplicating surface of the gelatin band. The carriage is then moved to roll the platen roller over the 20 entire surface of the sheet of paper in the duplicating process.

It is desirable in these machines to have ready 25 access to the pressure roller and platen roller for such purposes as cleaning, inspecting, and the like. The paper guide plate or support lies over the pressure roller so that it has heretofore been difficult to get at the rollers.

It is a purpose of this invention to provide in a 30 machine of this character a paper guide or support that is movable out of the way in order that the operator can have ready access to the pressure roller.

It is also a purpose of this invention to movably 35 mount the pressure roller and paper guide together so that they may be moved out of the normal operating position and out of the carriage frame.

A further purpose of this invention is to provide 40 a carriage having the pressure roller and paper guide pivotally mounted on the carriage to swing up out of operating position to give access to the pressure and platen rollers.

Other objects and advantages will appear as 45 the description progresses in connection with the accompanying drawings in which—

Fig. 1 is a plan view of the carriage showing it 50 mounted on the frame of the machine over the platen;

Fig. 2 is an elevation partly in section of a carriage showing it in position on the machine;

Fig. 3 is a section substantially on the line 3—3 of Fig. 1;

Fig. 4 is a section on the same line with the

paper guide and pressure roller in raised position;

Fig. 5 is a section on the line 5—5 of Fig. 3;

Fig. 6 is an enlarged detail taken at one side of the paper guide looking upward at the lower surface thereof.

Referring to the drawings wherein a preferred embodiment of the invention is illustrated, A designates a portion of the frame of the duplicating machine, B designates a flat platen mounted on the frame A, and C designates the carriage which 10 is slidable lengthwise of the frame A and which is adapted to apply a sheet of paper to the gelatin band D which extends over the platen B.

The carriage has mounted therein the platen roller 10 which is pivotally supported by means of 15 platen arms 11, there being one of these arms at each side of the carriage, and these arms are in turn fixed upon the shaft 12 which is journalled in suitable bearings in the carriage frame. The operating handle or arm 13 is also fixed to shaft 20 12 for raising and lowering the platen roller, and suitable springs 14 are secured to the carriage frame and the platen arms to normally urge the platen roller into raised position.

The paper guide or support is indicated at 15. 25 This support is carried on a pair of arms 16 and 17 which arms are in turn pivoted by means of the pins such as 18 to the carriage frame. The paper guide is bolted to the arms by means of an 30 inturned portion 18' on the arm and the bolt 19. Each of the arms also has an extension indicated by the numeral 20 (see Figs. 3 to 6) which is 35 formed to fit snugly down on the carriage frame as indicated at 21 in Fig. 3, and the carriage frame has the upstanding lugs 24, one at each side apertured to receive the locking pins 25 on the extensions 20.

These locking pins, it will be evident from an 40 inspection of Fig. 5, are merely spring pressed by means of the spring so as to normally extend into the opening 27 in the extension 24 so that the operator by pulling out on the pins 25 may release the paper support or guide and lift it up from the normal operating position shown in Fig. 3 to the position shown in Fig. 4. This 45 puts the paper guide up out of the way and permits ready access to the pressure roller 28 and to the platen roller 10 as well as to the other parts in the carriage.

The pressure roller 28 is also supported on the 50 arms 16 and 17 for a limited pivotal movement as will now be explained. Each of the arms 16 and 17 has pivoted thereon an arm 29, and the shaft of the pressure roller is journalled in the arms 29. These arms 29 have the openings 30 55

therein which are somewhat larger than the pins 31 which are fixed on the arms 16 and 17 and which extend into the openings 30. Thus the arms 29 may swing a limited amount by their pivots to permit adjustment of the pressure roller in its cooperation with the platen roller.

In order to apply pressure between the rollers, I utilize springs 32. Each spring 32 has one end connected to pin 33 on its arm 29, and the other end is connected to stud 34 which is mounted on the inturned extension 18' found on each of the arms 16 and 17. The springs 32 being under tension, urge the pressure roller toward the platen roller as shown in Fig. 3.

15 In the normal operating position, the pressure roller 28 and the paper guide 15 are in the position shown in Fig. 3, and are held locked in this position by means of the pin 25 fitting in the openings 27 on the carriage frame extensions 24. 20 The platen roller may be elevated and lowered in the usual fashion. The rubber stop 35 on the platen arm is adapted to engage a shoulder 36 on the carriage frame to limit the upward movement of the platen roller. Now, however, 25 when it is desired to get at the pressure roller 28 and platen roller 10 for other purposes, the pins 25 are pulled out, and arms 16 and 17 and with them the paper guide 15 and pressure roller 28 are lifted up into the position shown in Fig. 4. 30 It will be evident from this figure that the pressure roller is in position to be readily cleaned without any difficulty. Furthermore, the springs 32 are accessible, and the platen roller 10 is also readily accessible for cleaning.

35 When it is desired to put the carriage back in operating position, the arms 16 and 17 are swung back to the position shown in Fig. 3. To do this, it is not necessary to pull out the pins 25 since their inner ends are rounded and since 40 they engage upon the rounded surfaces 37 on the carriage frame (see Fig. 5) which act as cams to push the pins out. When the extensions 20 rest solidly upon the carriage frame, the pins 25 will be lined with the openings 27 and will then 45 slide into these openings under the pressure of the springs 26.

While a certain embodiment of the invention has been shown and described, it is to be understood that it is capable of many modifications. 50 Changes, therefore, in the construction and arrangement may be made without departing from the spirit and scope of the invention as disclosed in the appended claims in which it is intended to claim all novelty inherent in the invention as broadly as possible in view of the prior art.

Having thus described the invention, what I claim as new and desire to secure by Letters Patent is:

1. A carriage for duplicating machines having mounted thereon a platen roller, a pressure roller, and a paper guide, the paper guide being stationary on said carriage in normal operating position and being movable out of normal operating position to provide for ready access to said rollers.

2. A carriage for duplicating machines having a paper guide pivotally mounted thereon for swinging movement between normal operating position, and a second position outside the carriage to provide ready access to the carriage parts.

3. In a carriage for duplicating machines, a pressure roller, and means mounting said roller

on said carriage for movement between operating position within the carriage and cleaning position outside the carriage.

4. In a carriage for duplicating machines, a pressure roller, and means mounting said roller 5 on said carriage for movement between operating position within the carriage and cleaning position outside the carriage, and a paper guide carried by said mounting means.

5. A carriage for duplicating machines having 10 a platen roller, a pressure roller, and a paper guide, said pressure roller and paper guide being pivotally mounted in said carriage and movable out of said carriage about its pivotal mounting, and means on said carriage for holding said paper guide stationary with respect to the carriage.

6. A carriage for duplicating machines having a platen roller, a pressure roller, and a paper guide, the paper guide being movable out of 20 normal operating position to a position outside of the carriage to provide for ready access to said rollers, and means to hold said guide in normal operating position.

7. A carriage for duplicating machines having a platen roller, a pressure roller, and a paper 25 guide, the paper guide and pressure roller being movable out of normal operating position and above said carriage to provide for ready access to said rollers, and means to hold said guide and said pressure roller in normal operating position. 30

8. A carriage for duplicating machines having a platen roller, a pressure roller, and a paper guide, a pair of arms pivoted on the carriage and fixed to said guide for pivotally mounting the guide, the arms having means thereon for supporting said pressure roller. 35

9. A carriage for duplicating machines having a platen roller, a pressure roller, and a paper guide, a pair of arms supporting said paper guide with the lower end thereof normally extending 40 into the carriage above the pressure roller, said arms being movably mounted to said carriage to move said guide out of the carriage and thereby render the interior of the carriage more accessible. 45

10. A carriage for duplicating machines having a platen roller, a pressure roller, and a paper guide, means providing a supporting framework for said pressure roller and paper guide, said means being pivoted to said carriage about an axis 50 spaced from the paper guide whereby movement of said means about its axis will move the paper guide and pressure roller clear of the carriage, and lock means for locking the paper guide and pressure roller in functionally operative position 55 within the carriage.

11. A carriage for duplicating machines comprising a carriage, a platen roller mounted therein, a paper guide mounted in said carriage in position to direct sheets toward said platen roller, 60 and mounting means for said guide movable with respect to said carriage to elevate said guide above the carriage.

12. A carriage for duplicating machines comprising a carriage, a platen roller mounted therein, a paper guide mounted in said carriage in position to direct sheets toward said platen roller, mounting means for said guide movable with respect to said carriage to elevate said guide above the carriage, and a pressure roller carried 70 by said mounting means.

ALFRED MARCHEV.
